NICHOLAS S. VEDDER, OF TROY, AND TOBIAS S. HEISTER, OF LANSINGBURG, NEW YORK, ASSIGNORS TO NICHOLAS S. VEDDER.

Design No. 4,243, dated July 19, 1870.

DESIGN FOR STOVE-PLATES.

The Schedule referred to in these Letters Patent and making part of the same

To all whom it may concern:

Be it known that we, NICHOLAS S. VEDDER, of Troy, and TOBIAS S. HEISTER, of Lansingburg, in the county of Rensselaer and State of New York, have jointly invented and produced certain new and original features in Designs for Stove-Plates, of which the following is a specification, reference being had to the accompanying photographic representation of a stove having our new design.

One new part of our design consists of the rows of ornaments, *r s t*, shaped and arranged together upon, and cast with, and forming the distinguishing feature of, the design for the top-plate *U*, as shown in the aforesaid photograph.

Another new feature of our design is the combination of the rows of ornaments *z w x y*, shaped and arranged together, as shown in the photograph afore-

said, and constituting the design for the bottom-plate *V* of a stove, and

Another part of our invention consists of the damper-frame *W*, shaped, arranged, and ornamented in its various parts as shown in the accompanying photograph.

What we claim as our invention and production, and desire to secure by Letters Patent, is—

1. The ornamental design for the top-plate *U*, as herein described and shown.
2. The design for the bottom-plate *V*, as shown and described.
3. The design for the damper-frame *W*, as shown.

NICHOLAS S. VEDDER.
TOBIAS S. HEISTER.
